UNITED STATES PATENT OFFICE.

CHARLES E. NELLIS, OF BROOKLYN, NEW YORK, ASSIGNOR TO GRINDEN ART METAL COMPANY, A CORPORATION OF NEW YORK.

METALLIC STRUCTURE, SUCH AS DOORS AND THE LIKE.

964,676.

Specification of Letters Patent. Patented July 19, 1910.

Application filed May 26, 1909. Serial No. 498,400.

To all whom it may concern:

Be it known that I, CHARLES E. NELLIS, a citizen of the United States, and a resident of the borough of Brooklyn, county of 5 Kings, and State of New York, have invented certain new and useful Improvements in Metallic Structures, Such as Doors and the Like, of which the following is a full, clear, and exact description, reference being 10 had to the accompanying drawings, forming part of this specification.

My invention relates to metallic structures, such as doors, frames, windows and panels.

Among the objects of my invention are 15 the production of such a structure, which shall be attractive in appearance, strong and durable; relatively light in weight; economically manufactured; quickly and accurately assembled, and which shall be 20 capable of withstanding a high degree of heat and sudden changes in temperature.

Further objects of my invention will be hereinafter referred to, in the detailed description of a structure embodying the same.

25 For the purpose of briefly and clearly describing my invention, I have selected for illustration and description, a metallic door embodying my invention in a preferred form; but it is to be understood that the invention is applicable to numerous structural parts besides doors and also that the particular details described, are susceptible of various modifications, not involving a departure from the invention.

30 Figure 1 of the drawings, is an elevation of a door embodying my invention; Fig. 2 is a vertical section on a larger scale, on the line 2—2, (Fig. 1); Fig. 3 is a sectional view of the structural parts unassembled, shown 35 in Fig. 2; Fig. 4 is a sectional view on the line 4—4, (Fig. 1); Fig. 5 is a similar view on the line 5—5, (Fig. 1); and Fig. 6 is an unassembled view in section, of the parts shown in Fig. 5.

40 Similar reference characters are employed to designate like parts in all the views.

The particular structure illustrated comprises frame members, to wit: the stiles 1 and 2, and the top, bottom and lock rails 3, 45 4 and 5, and the panels 7 and 8. The stiles 1 and 2, and the rails 3, 4 and 5 are formed with opposing walls 9 and 10, (Fig. 5), and are connected by means of an interlocking joint which forms one of the features of my 50 invention, and is illustrated in Figs. 5 and

6. This joint is formed by bending the edges of the walls 9 of one member, (preferably a stile), back upon itself, and again bending or recurring them in a substantially parallel plane so as to form a slot or groove 60 11, of substantially the same width as the thickness of the metal, with a flange 12 projecting beyond the first bend.

A reinforcing member 14, is secured to the flanges 12, either by riveting or welding it 65 thereto, the extension of the flanges 12, permitting this to be accomplished with great facility, and without defacing the exterior of the structure. The edges of the other member, preferably a rail, are bent in a substantially similar manner, but without the slot 11, and the projecting flanges 15, of the second member are inserted into the slots 11 of the first member. The frame members are thus provided with shoulders 16 which 70 abut against the shoulders on the other frame members when the flanges 15 are inserted into the slots 11, forming a flush joint between the members. If desired, in finishing the structure, this joint may be filled 75 and suitably finished to present a smooth surface, entirely concealing the joint. The frame members may be further secured in position by rivets or by brazing or welding 80 the joints.

85 It is essential, in doors and other structures of this character, that they should possess the capacity of withstanding a high degree of heat and extreme changes in temperature without buckling or becoming sufficiently distorted to separate or part from the frames. This is particularly true of the panel members, which from a heat-resisting standpoint, are the most vulnerable points of the structure. I therefore provide 90 a yielding connection between the panel and frame members of the structure, which, while securing the necessary rigidity of construction, will permit a slight but sufficient relative movement of the members, due to 95 expansion and contraction, under high or extreme changes in temperature. This feature of my invention is illustrated in Figs. 2, 3 and 4. The panel member 8, is preferably formed of two plates or sheets, which, 100 adjacent to their edges are each formed with a double bend, similar to the bend formed in the frame members as heretofore described, providing if desired a molding-receiving 105 slot or recess 20, and a shoulder 21. The 110

edges of each plate are projected beyond the shoulders 21, to form an extension 22, the extension of one plate resting against the extension of the opposite plate. If desired, 5 these extensions may be rigidly secured together by riveting or welding. This construction provides a dead air space 24, between the two plates, which will largely prevent the conduction of heat between the 10 panel plates. A member 25, preferably of inverted channel form, fits tightly but slid- 15 ingly between the walls of the reinforcing member 26, secured to the flanges 29, of the frame members as above described. In the form shown, the member 25, is provided 20 with a recess 27, which receives the ends of the panel extensions 22. The latter are rigidly secured in place by riveting or otherwise. Thus the panels are supported in position rigidly against lateral movement but 25 yieldingly with respect to any inward or outward movement of the edges due to contraction or expansion of the metal.

The slots or recesses 11, which I have de- 25 scribed and shown as being formed in the stiles 1 and 2, and as receiving the project- 30 ing flanges formed on the rails, as will be understood extend the entire length of the stiles, and the inner edges of the walls of the rail members 3, 4 and 5 are bent to form similar slots 28, and flanges 29. The slots 35 11 on the stiles, and 28 on the rails thus extend completely around the panel spaces. Moldings 30, which surround the panels, 40 are provided on each edge with flanges 31 and 32. The flanges 31, extend into the slots 20, on the panels, and the flanges 32 into the slots 11 and 28 on the stiles and rails re- 45 spectively, the construction shown permit- 50 ting the moldings to be inserted lengthwise during the assembling of the structure, and they are thus firmly held in position without other fastening means.

A structure of the character described, 45 embodying my invention, possesses great ri- 50 gidity owing to the reinforcement of the interior margins of the frame members, pro- 55 duced by the bending of the edges of the members back upon the sheet to form the abutting shoulders and flange-re- 60 ceiving slots. Furthermore the different mem- 65 bers of the structure can be assembled by comparatively unskilled labor with great facility and accuracy, and when completed, 70 the structure presents smooth surfaces at all points, unmarred by any external fastening means, such as rivets, screws or bolts, for se- 75 curing the moldings or the panel members to the frame.

80 In describing the manner of interlocking the stiles and rails, I have, to avoid pro- 85 llixity, illustrated and described the slots as formed on the stiles, and the coöperating flanges as formed on the rails, but it will 90 of course be understood, that a mere reversal

of this arrangement would be within the scope of my invention.

I claim:

1. A metallic structure of the character described, having members whose surfaces 70 lie in substantially the same plane, one of said members being formed with a shoulder and with a slot and a flange projecting be- 75 yond the shoulder, and the other member being formed with a shoulder which abuts 80 against the shoulder of the first mentioned member, and with a flange which projects into said slot, substantially as set forth.

2. A metallic structure of the character described, containing interlocking members, 80 one member of which has its edge bent back upon itself and recurved in a substantially parallel plane to form a slot, and a flange 85 projecting beyond the first bend; another member provided with a flange extending into said slot; and a reinforcing member secured to the projecting flange of the first mentioned member, substantially as set forth.

3. A metallic structure of the character 90 described, containing interlocking members, one member of which has its edge bent back upon itself and recurved in a substantially parallel plane to form a slot, and a flange 95 projecting beyond the first bend; another member provided with a flange extending into said slot and offset to provide a flush joint; and a reinforcing member secured to the projecting flange of the first mentioned member, substantially as set forth. 100

4. A metallic structure of the character described, containing interlocking members, one member of which has its edge bent back upon itself to form a shoulder, and recurved in a substantially parallel plane to form a 105 slot and a flange projecting above the shoul- 110 der, another member having its edge bent back upon itself to form a shoulder abutting against the shoulder on said first mentioned member and recurved in a substantially parallel plane to form a projecting flange 115 extending into said slot, substantially as de- 120 scribed.

5. In a metallic structure of the character described, having interlocking members, one 115 member of which has its edge bent to form a slot to receive the other member and to form a flange projecting beyond the slot, and an interior reinforcing member secured to the 120 projecting flange, substantially as set forth. 125

6. In a metallic structure of the character described, a hollow member having oppo- 125 sitely disposed walls, the edges of which are bent to form flange-receiving slots with flanges projecting beyond the slots, and a re- 130 inforcing member connecting the flanges of the opposite walls and secured to the inner sides thereof.

7. In a metallic structure of the charac- 130 ter described, the combination of frame

members having oppositely disposed walls, a movable member arranged between said walls and a panel member rigidly connected to said movable member.

- 5 8. In a metallic structure of the character described, the combination of a frame member having oppositely disposed walls bent adjacent to their edges to form molding-receiving slots, a panel formed of separated plates bent to form molding-receiving slots and having their edges projected beyond the slots, a member slidably mounted between the walls of the frame member and secured to the edges of the panel and moldings having flanges extending into the slots on the frame member and panel.
9. In a metallic structure of the character described, the combination of a frame member having oppositely disposed walls, a channel-shaped reinforcing member secured at its sides to the edges of said walls, a movable member slidably mounted in said channel member and a panel member rigidly secured to said movable member.
- 25 10. In a metallic structure of the character described, the combination of frame members having oppositely disposed walls bent adjacent to their edges to form molding-receiving slots, panel members formed of separate plates bent to form molding-receiving slots and moldings held in position by flanges thereon extending into the slots on the frame and panel members.
- 30 11. A panel for a metallic structure of the

character described, consisting of two separated plates, each having an edge bent inwardly to form a molding-receiving slot and extended beyond the slot to form a fastening connection common to both plates. 35

12. A panel for a metallic structure of the character described consisting of two separated plates having their edges bent inwardly and backwardly and then extended forwardly beyond the bend to form a fastening connection common to both plates. 40 45

13. In a metallic structure of the character described the combination of frame members, a panel member consisting of two separated plates having their edges bent inwardly into contact with each other and extended beyond the bend to form a fastening projection common to both plates, and a yielding connection between such projection and the frame members. 50

14. In a metallic structure of the character described, the combination of frame members, a panel member consisting of two separated plates having their edges bent inwardly and backwardly into contact with each other and extended forwardly beyond the bend to form a fastening projection common to both plates and a yielding connection between said projection and the frame members. 55 60
